[57] CLAIM

The ornamental design for a personal computer, as shown and described.

DESCRIPTION

FIG. 1 is a top, front and right side perspective view of a personal computer according to our design;
FIG. 2 is a top plan view thereof;
FIG. 3 is a front elevational view thereof;
FIG. 4 is a right side elevational view thereof;
FIG. 5 is a left side elevational view thereof;
FIG. 6 is a rear elevational view thereof;
FIG. 7 is a bottom plan view thereof;
FIG. 8 is a top, front and right side perspective view of a second embodiment of a personal computer according to our design;
FIG. 9 is a top plan view thereof;
FIG. 10 is a front elevational view thereof;
FIG. 11 is a right side elevational view thereof;
FIG. 12 is a left side elevational view thereof;
FIG. 13 is a rear elevational view thereof;
FIG. 14 is a bottom plan view thereof;
FIG. 15 is a top, front and right side perspective view of a third embodiment of a personal computer according to our design;
FIG. 16 is a top plan view thereof;
FIG. 17 is a front elevational view thereof;
FIG. 18 is a right side elevational view thereof;
FIG. 19 is a left side elevational view thereof;
FIG. 20 is a rear elevational view thereof; and,
FIG. 21 is a bottom plan view thereof.
